(57) **CLAIM**

The ornamental design for a bottle as shown and described.

DESCRIPTION

FIG. 1 is a top view of a bottle according to the invention;

FIG. 2 is a left side view of the bottle of FIG. 1;

FIG. 3 is a front view of the bottle of FIG. 1;

FIG. 4 is a right side view of the bottle of FIG. 1;

FIG. 5 is a back view of the bottle of FIG. 1;

FIG. 6 is a front right side view of the bottle of FIG. 1;

FIG. 7 is a perspective view of the bottle of FIG. 1; and,

FIG. 8 is a bottom view of the bottle of FIG. 1.

This design is directed to a bottle. Any broken lines show unclaimed subject matter only and form no part of the claimed design.
